UNITED STATES PATENT OFFICE.

CHARLES HASSINGER, OF PLYMOUTH, MICHIGAN.

DOOR-CHECK.

SPECIFICATION forming part of Letters Patent No. 249,761, dated November 22, 1881.

Application filed September 7, 1881. (No model.)

To all whom it may concern:

Be it known that I, CHARLES HASSINGER, of Plymouth, in the county of Wayne, Michigan, have invented an Improvement in Door-Stops, 5 of which the following is a specification.

The nature of this invention relates to new improvements in the construction of door-stops of that class designed to hold the door open; and the invention consists in the peculiar construction and arrangement of the parts, all as 10 more fully hereinafter set forth and claimed.

In the accompanying drawings, which form a part of this specification, my invention is shown in Figure 1, in perspective, as applied to 15 a door, and in Fig. 2 a detached and enlarged view.

A represents a suitable plate, designed to be secured to the floor by means of screws *a*. This plate is provided upon one side or edge with 20 a hook-projection, *b*, and the studs *c*.

B is a bail, the bend of which is designed to engage with the hook-projection *b* and to loosely turn in the same.

In practice, where the bottom of the door

swings sufficiently above the floor, the plate *A* 25 is screwed to the floor at the point it is desired to hold the door open, the bail *B* being raised, so that one arm will be upon each side of the door, the bail resting upon the studs *c*, which prevent it from falling back upon the floor. 30 When it is desired to close the door the bail is tipped back, so that it will rest upon the floor in the position shown in dotted outlines. Where the door swings too close to the floor to admit of the above arrangement, the device may be 35 placed so that the corner of the door will clear the plate in being opened or closed, and still the bail will engage with the edge of the door when it is raised up.

What I claim as my invention is— 40

In a door-stop, the plate *A*, provided with lugs *c*, and the bail *B*, pivoted to the plate *A*, and adapted to rest against the lugs *c*, substantially as and for the purpose specified.

CHARLES HASSINGER.
